ARTHUR L. METTLER, OF LOMITA, CALIFORNIA

VALVE-SPRING-LIFTING TOOL

Application filed February 18, 1929. Serial No. 340,977.

My invention relates to valve spring lifting tools for use in compressing the coil spring around the stem of a poppet valve for internal combustion engines to release 5 the tension of the spring upon its supporting pin so that the pin may be withdrawn and the valve removed.

A purpose of my invention is the provision of a valve spring lifting tool having link 10 connections between the movable parts thereof which functions to cause the movable jaw of the tool to move in a line which for all practical purposes is straight and at right angles to the stationary jaw of the tool 15 whereby, the spring compressing force created by movement of the jaw is applied vertically along the axis of the spring in consequence of which the tool is made operable to compress the spring with a minimum 20 application of force. My link connections also provide a means for compounding the power manually applied to the tool in its transmission to the jaws of the tool and so that such transmission is direct rather than 25 indirect as in previously conceived tools of this character. Such a power compounding means results in the production of a tool that is operable to compress relatively heavy 30 springs such as are found in large internal combustion engines and with the application of a minimum amount of force.

It is also a purpose of my invention to provide a tool in which that jaw thereof adapted to engage the valve spring seat, is 25 formed with a face shaped to provide a substantially knife edged contact with the valve spring seat, and one that for all practical purposes is maintained centrally of the seat during spring compressing movement of the jaw, whereby, the force exerted by the 40 jaw is so applied that the seat will not be moved laterally and hence cannot have binding engagement with the valve stem to interfere with compression of the spring by the 45 tool.

I will describe only one form of valve spring lifting tool embodying my invention, and will then point out the novel features thereof in claims.

In the accompanying drawings;

Fig. 1 is a view showing in side elevation one form of valve spring lifting tool embodying my invention with the jaw thereof closed and in applied position to a poppet valve.

Fig. 2 is a view similar to Fig. 1 showing the jaws of the tool in open position in the act of compressing the valve spring.

Fig. 3 is a view showing the tool in top plan view and in applied position to the valve spring seat.

Fig. 4 is a view showing the tool in end elevation.

My invention in its present embodiment comprises specifically a lever S having at 65 one end a bifurcated jaw 15 and at the other end a handle 16, preferably round and knurled as indicated. Between the handle and the jaw the lever S is provided with an ear 17 receiving a pin 18 for pivotally 70 mounting a pair of links 19 on the ear, the upper ends of the links being pivotally connected to an ear 20 of a lever M by means of a pin 21. This link connection provides a shiftable or floating fulcrum for the lever 75 M as will be understood from the description of the operation of the tool. The lever M is likewise provided with a jaw 22 which is bifurcated and shaped in a particular form as will be described hereinafter.

To the rear of the ear 17 the lever S is provided with a pair of ears 23 receiving a pin 24 to provide a pivot for an operating lever L that is provided with a round and knurled handle 25. This operating lever is 85 operatively connected to the lever M by means of a pair of links 26 pivoted on the lever L at the point indicated at 27 and on the rear end of the lever M as indicated at 28. A second connection between the levers 90 L and M is also provided which consists of a pair of links 29, the lower ends of which are connected to the lever L between the pivots 24 and 27 as indicated at 30. The upper ends of the links are pivoted on the lever M as indicated at 31 and the location of this pivot is such that the links occupy an inclined position.

For retaining the lever L in the active position shown in Fig. 2 wherein the jaws 100

15 and 22 are separated or opened, I provide a latch comprising a yoke 32 pivoted on the handle 16 so as to be movable to embrace the handle 25 as illustrated in Fig. 2. To secure the handle 25 in other positions between fully opened and fully closed position, the handle 25 is provided with a tongue 33 having notches 34 therein in any one of which the yoke 32 is adapted to seat. As clearly illustrated in Fig. 4, the end of the handle 16 is provided with a slot 35 in which the tongue 33 is adapted to be received to permit the yoke 32 to embrace the handle 25 or to permit the yoke to enter the gage within the notches 34. As shown in Fig. 4, the upper edge of the slot has the side walls thereof curved outwardly as indicated at 36 to provide a tapered entrance for the end of the tongue 33 in order that 20 the tongue may readily enter the slot as will be understood.

In practice, the tool is applied in the manner illustrated in Fig. 1, the jaws 15 and 22 being in closed position so that they may be readily extended beneath the valve spring seat indicated at 37 and the top of the valve operating rod indicated at 38. The jaw 15 actually rests on a head 39 of the rod 38 to form a support for the lever S so that in actual operation the lever S is stationary.

To compress the valve spring indicated at 40 the handle 25 is moved downwardly to the position shown in Fig. 3, and during such movement the lever M is rocked on its fulcrum 21 through the link connection 26 so that the jaw 22 is moved upwardly to the open position shown. Through this link connection 26 the power applied to the lever L is directly transmitted to the lever M, and by reason of the relative positions of the pivots of the two levers and the link connection, it will be manifest that movement of the lever L is compounded in 45 its transmission to the lever M.

As previously expressed herein, a purpose of my invention is to move the jaw 22 in a straight line substantially, and one at right angles to the jaw 15 in order that a true vertical force will be applied to the spring in effecting its compression. Such movement of the jaw 22 is effected by operation of the lever L and in the following manner: As the lever L moves downwardly the links 29 exert a pull on the lever M which is rearwardly, thereby causing the links 19 to swing rearwardly about the pivot 18 so as to rearwardly shift the fulcrum 21 for the lever M. Thus the lever M is moved rearwardly as it is rocked so that the jaw 22, instead of moving upwardly in an arc as would be the case if the fulcrum 21 was fixed, moves vertically and substantially in a straight line. In consequence of this operation the force exerted by the rising jaw

22 acts along or in parallelism with the longitudinal axis of the spring, thus permitting the tool to compress the spring with greater ease than would be possible with a tool where the jaw moves in an arc.

As illustrated, the jaw 22 is offset with respect to the lever M, and its upper or working surface is of convex form in order to provide a substantially knife edge contact with the spring seat 37. In consequence of this knife edge contact the lifting force exerted by the jaw is imposed on the seat 37 at points which for all practical purposes are non-shiftable, and hence fixed, and as these points of contact are across the center of the spring seat, the seat in its rising movement will not be shifted to one side or the other but will be maintained horizontally and thus moved without binding engagement with the valve stem.

Although I have herein shown and described only one form of valve spring lifting tool, embodying my invention, it is to be understood that various changes and modifications may be made herein without departing from the spirit of the invention and the spirit and scope of the appended claims.

I claim:

1. In a valve spring lifting tool, a pair of levers having jaws, a link connection between the levers providing a shifting fulcrum for one of the levers, an operating lever pivoted on the other lever, a link connection between the operating lever and the first mentioned jaw lever by which movement of the operating lever swings the jaw lever and compounds its movement, and a second link connection between the operating lever and the said jaw lever for shifting the latter as it swings so that its jaw moves in a path substantially straight and at right angles to the jaw of the other lever.

2. A valve spring lifting tool comprising a pair of levers having jaws, means connecting the levers for actuating one of the levers so that its jaw moves in a straight line substantially and at right angles to the jaw of the other lever, the jaw of the first lever having an outer face formed with a convex portion so positioned that when the tool is applied to a valve said convex portion will engage the valve spring seat in such manner that upon actuation of the corresponding lever the jaw will exert an upward force on said seat to compress the valve spring and in a manner to maintain said seat centered on the valve stem to prevent binding thereof.

3. In a valve spring lifting tool, a pair of pivoted levers having handles, one of said handles having a slot therein, a yoke pivoted on the slotted handle, and a tongue fixed on the other handle and positioned to be extended within said slot, said tongue having notches in any one of which said yoke may

engage for latching the two handles against separation.

4. In a tool as embodied in claim 3 wherein the walls of the slot are beveled at their edges to facilitate entrance of the tongue into the slot.
